DESIGN FOR A SHOE OR SIMILAR ARTICLE

Leo Sholtz, New York, N. Y.

Application November 6, 1939, Serial No. 88,073

Term of patent 3½ years

To all whom it may concern:

Be it known that I, Leo Sholtz, a citizen of the United States, residing in New York city, in the county of New York and in the State of New York, have invented a new, original, and ornamental Design for a Shoe or Similar Article, of which the following is a specification, reference being had to the accompanying drawing, forming part thereof.

Figure 1 is a plan view of a shoe showing my new design.

Figure 2 is a side elevation of the shoe, partly in perspective.

The dominant feature of my design resides in a shoe having a strap extending across the open instep of the shoe, the ends of the band having a rolled formation and being attached to the ends of the vamp in combination with a second strap looped over the middle of the first strap, its ends having a looped formation and attached to the forward portion of the vamp.

I claim:

The ornamental design for a shoe or similar article, substantially as shown and described.

LEO SHOLTZ.
